UNITED STATES PATENT OFFICE

FREDERIC BULL AND FRANK WHITE, OF WALSALL, ENGLAND

NONSKID DEVICE FOR THE WHEELS OF ROAD VEHICLES

Application filed September 9, 1929, Serial No. 391,420, and in Great Britain March 25, 1929.

This invention relates to non-skid devices for the wheels of road vehicles of the kind comprising a number of chains or flexible members arranged across the tread of the tyres. In connection with this type of non-skid device considerable difficulty has been experienced in producing a construction having a reasonable length of life, most of the constructions hitherto employed showing excessive wear after only a relatively short period of use. Furthermore in the known constructions, even where rollers were employed as wearing pieces, the wearing pieces bore on the tyre and so wore the latter unduly.

The primary object of the present invention is to construct a non-skid device which will be effective in use and relatively cheap to produce and which will have a longer life than those hitherto commonly employed, and which in addition will not unduly wear the tyre over which it is placed.

Referring to the drawings:

Figure 1 is a side view of a wheel with a non-skid device constructed according to one form of this invention applied thereto.

Figure 2 is a perspective view of a part of one form of non-skid device constructed according to this invention.

Figure 3 is a fragmental plan of the same.

Figure 4 is a fragmental sectional elevation of the same.

Figure 5 is a part sectional elevation of a modified construction of non-skid device constructed according to this invention.

Figure 6 is a plan of a part of a further modified construction of non-skid device according to this invention.

Figure 1 is drawn to a smaller scale than the remainder of the figures.

Referring to Figures 1 to 4 of the drawings, 1 is the wheel, 2 are chains adapted to be annularly arranged around the rim of the wheel, one on each side thereof, and 3 are transverse chains secured at each of the opposite ends 4 to one of the annular chains 2. The chains 3 extend across the wheel transversely of the main plane thereof. Each of the transverse chains 3 comprises a number of links 5, between the inner ends of

which is located a link 6. The link 6 is preferably of plate form of suitable thickness and is provided with a pair of openings 7. The link 6 thus constitutes a pair of adjacent closed loops and the link is provided with an eye 8 at each end by which the links 5 are connected to it. An integral arm 9 extends from one end of the link 6 and may conveniently form an extension or a portion of one of the eyes 8, and this integral arm 9 is bent so as to have a spindle portion 10 which lies adjacent the surface of the links 6 and extends centrally longitudinally thereof as shown.

A wearing member 11 which is conveniently in the form of a roller is mounted on each edge of the spindle 10 adjacent each of the openings 7 so that a part of one of these rollers extends into each of the openings and the rollers can rotate freely on the spindle 10. More than one roller can be mounted adjacent each opening 7 if desired.

If desired the link 6 may only have one opening 7 instead of two, or it may have any other number of openings.

The link 6 is recessed at 12 and the end 13 of the spindle 10 is located in this recess and is prevented from moving laterally of the link 6 by this means.

The ends of the link 6 and particularly the parts forming the eyes are bent out of the main plane of the link so that when the link is in use, its longitudinal shape corresponds approximately to the shape of the tyre on which the device is placed.

In the modified arrangement shown in Figure 5, the spindle 10 is formed separately of the link 6 and is provided with down-turned ends 14 which are passed through holes 15 in the link and are riveted over at 16 so that the part 10 of the spindle is parallel for its main part with the link 6. In this case both ends of the link are in the form of a complete eye 8.

In the modification shown in Figure 6, the link 6 is constructed, and each spindle is attached to the link, in a similar manner to that described with reference to Figure 5, and the only difference is that the link is constructed so as to receive four wearing

members or rollers 11 and to this end four of the recesses 7 are provided and they may be arranged in any suitable manner. They are shown arranged in a rectangular formation, but if desired three rollers could be used which could be arranged in triangular formation. Any other formation and number of rollers may be employed and these need not be all on the same axis.

Further, if required additional means in the form of projections may be formed on the link to prevent lateral displacement of the arm which bears the wearing member or members.

In another arrangement, the main part of the link may be provided with a hole, the axis of which extends parallel to the plane of the link, and the straight part of the arm which bears the wearing member or members may extend through or into this hole.

What we claim then is:—

1. In a non-skid device a plate element, a spindle on said plate, and a roller on said spindle, the roller being adapted to take the majority of the wear to which the non-skid device is subjected by its engagement with the road.

2. In a non-skid device a plate element, means for connecting said plate to the other parts of the non-skid device, a spindle on said plate, a roller on said spindle, the said plate having a recess into which the said roller projects, the roller being adapted to take the majority of the wear to which the non-skid device is subjected by its engagement with the road and being carried so as to be clear of the tyre.

3. In a non-skid device a plate element, a spindle on said plate and a roller on said spindle, the roller projecting outwardly beyond one surface of the plate and also projecting into but not through the plate, the roller being adapted to take the majority of the wear to which the non-skid device is subjected by its engagement with the road.

4. In a non-skid device a plate element, means for connecting said plate to the other parts of the non-skid device, a spindle on said plate, a roller or rollers on said spindle, each roller projecting outwardly beyond one surface of the plate and also projecting into but not through the plate, the outwardly projecting part or parts of the roller or rollers being adapted to take the majority of the wear to which the non-skid device is subjected by its engagement with the road.

5. In a non-skid device a plate element having an eye at each end for attaching it to the other parts of the non-skid device, a spindle on said plate and outside the plane of the plate, a roller or rollers on said spindle, each roller projecting outwardly beyond one surface of the plate and also projecting into but not through the plate, the plate having an aperture for each roller into which the roller

projects and by the ends of which the axial movement of the roller is limited, and the outwardly projecting part or parts of the roller or rollers being adapted to take the majority of the wear to which the non-skid device is subjected by its engagement with the road.

6. In a non-skid device a plate element, a spindle on said plate and integral with the plate, a roller on said spindle, each roller projecting outwardly beyond one surface of the plate and also projecting into but not through the plate, and the roller being adapted to take the majority of the wear to which the non-skid device is subjected by its engagement with the road.

7. In a non-skid device a plate element, having an eye at each end for attaching it to the other parts of the non-skid device, a spindle on said plate extending longitudinally of the plate and outside the plane of the plate, said spindle being integral with the plate and being twisted to form one of said eyes on the plate, means for preventing lateral movement of the spindle, a roller or rollers on said spindle, each roller projecting outwardly beyond one surface of the plate and also projecting into but not through the plate and the outwardly projecting part or parts of the roller or rollers being adapted to take the majority of the wear to which the non-skid device is subjected by its engagement with the road, whilst that side of the plate element from which the roller or rollers does or do not project is adapted to rest on the tread of the tyre.

8. In a non-skid device a plate element, a roller or rollers carried by the plate so as always to be out of contact with the tyre to which the non-skid device is applied and the roller or rollers being adapted to take the majority of the wear to which the non-skid device is subjected by its engagement with the road.

In witness whereof we affix our signatures.

FREDERIC BULL.

FRANK WHITE.
